Primary Examiner — Cynthia R Underwood

(74) *Attorney, Agent, or Firm* — Murray, Ziel & Johnston; Aaron Powell

(57) **CLAIM**

The ornamental design for a cable organizer, as shown and described.

DESCRIPTION

FIG. 1 is a top, front, right side perspective view of a cable organizer, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view showing the cable organizer in open state.
 The evenly dashed broken lines illustrate portions of the cable organizer and form no part of the claimed design.

1 Claim, 9 Drawing Sheets
